METERED POWER SUPPLY RACK ADAPTER

Edward Brenner, Commack, Marvin L. Price, Queens,
and Benjamin Shmurak, Lynbrook, N.Y., assignors to
Lambda Electronics Corporation, Huntington, N.Y., a
corporation of New York

Filed Aug. 15, 1969, Ser. No. 18,693

Term of patent 14 years

Int. Cl. D14—99

U.S. Cl. D26—1

FIG. 1

FIG. 2

FIG. 1 is a perspective view from the front of a metered power supply rack adapter embodying our new design; and

FIG. 2 is a perspective view of the metered power supply rack adapter of FIG. 1 illustrating same from the rear.

We claim:

The ornamental design for a metered power supply rack adapter, as shown.
